BEVERAGE VENDING MACHINE

Clare E. Hodgman, Mamaroneck, N.Y., assignor to The Coca-Cola Company, Atlanta, Ga., a corporation of Delaware

Filed Nov. 20, 1959, Ser. No. 58,413

Term of patent 14 years

(Cl. D52—3)

The opposite side of the vending machine is substantially the same in appearance as the side shown and the rear is unadorned.

The drawing is lined to indicate contrast in color.

I claim:

The ornamental design for a beverage vending machine, as shown and described.
